Primary Examiner — Elizabeth A. Albert(74) *Attorney, Agent, or Firm* — Emilio Cazares; Cazares Law(57) **CLAIM**

I claim the ornamental design for a pen, as shown and described.

DESCRIPTION

FIG. 1 is a perspective view of a pen showing the new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded, front view thereof.

The broken lines in the drawings are included for the purpose of showing features that form no part of the claimed design.

1 Claim, 5 Drawing Sheets(56)
